CABINET TYPE RADIANT HEATER

James Leonard Raulston, South Pittsburg, Tenn.

Application August 4, 1949, Serial No. 4,299

Term of patent 14 years

(Cl. D81—19)

To all whom it may concern:

Be it known that I, James L. Raulston, a citizen of the United States, residing at South Pittsburg, in the county of Marion and State of Tennessee, have invented a certain new, original, and ornamental Design for Cabinet Type Radiant Heater, of which the following is a specification, reference being had to the accompanying drawing, forming a part thereof, wherein:

The single figure of the drawing is a perspective view of a cabinet type radiant heater showing my new design.

Both sides of the cabinet are substantially identical.

I claim:

The ornamental design for a cabinet type radiant heater, as shown, and described.

JAMES LEONARD RAULSTON.
